UNITED STATES PATENT OFFICE

CHARLES HENNELL, OF INGLEWOOD, CALIFORNIA

CUSHION FILLING MACHINE

Application filed July 21, 1930. Serial No. 469,416.

This invention relates to cushion filling machines, and more especially to a machine of the pusher type capable of being operated by one person.

In the past, machines for filling upholstered furniture have been very ponderous and required a great deal of space in which to operate them. This entailed a great initial expenditure and a large operating cost due to the added space necessary for this machine, and the need of at least two people to operate it.

It is an object of my invention to improve the old type of mechanism by providing a device which can be readily operated by one person. I accomplish this by means of a simple mechanical assembly actuated by the operator and acting on the pusher rod to propel the filling material through the filling box and into the covering for the cushion.

It is another object of my invention to provide a plurality of dogs or fingers contacting with teeth on the pusher rod, one of said dogs acted on by the actuating means to push the pusher rod through the filling box, and the other dog preventing a backward movement of the pusher rod.

It is another object of my invention to provide a device acted on by the operator, to release holding means on the pusher rod in such a manner as to permit free backward movement thereof.

It is another object of my invention to provide a device which may be simply and cheaply constructed.

My invention possesses many other advantages, and has other objects which may be made more easily apparent from a consideration of one embodiment of my invention. For this purpose I have shown a form in the drawings accompanying and forming part of the present specification. I shall now proceed to describe this form in detail, which illustrates the general principles of my invention; but it is to be understood that this detailed description is not to be taken in a limiting sense, since the scope of my invention is best defined by the appended claims.

Referring to the drawings:

Figure 1 is a side elevational view of my cushion filling machine;

Fig. 2 is a plan view thereof;

Fig. 3 is a front end view with parts in section;

Fig. 4 is a detailed sectional view of a part of my machine; and

Fig. 5 is a section along the plane 5-5 of Fig. 4.

My machine comprises a base 10 having an upright support or standard 11 secured thereto. At the upper extremity of the standard 11, I provide a transverse support 12 (Figs. 1 and 4) extending parallel to and overlying a portion of the base 10. Intermediate the end of the support 12 and the base 10, I provide a reinforcing rod or stay 13.

Mounted on the support 12 is a telescoping filling box 14 adapted to contain the filling material. The box 14 is mounted on the support 12 so that the central portion thereof directly overlies the standard 11. The box 14 consists of two sections 15, 16 (Fig. 3) one telescoped within the other in order to provide a means for adjusting the width thereof to comply with the width of the cushion cover to be filled. The means for adjusting the width of the box 14 comprises a stationary screw 17 mounted in internally threaded blocks 18 and 19 and supported in the support 12. Integral with the blocks 18 and 19 are elevated extensions 20 secured at 21 to the sides 15, 16 of the box 14. The screw 17 has its ends threaded in opposite directions, so that by turning the crank 22 attached to the screw, in one direction the blocks 18, 19 carrying the sections 15, 16 will move in opposite directions on the screw 17 and thus make the width of the box 14 wider or smaller, depending on the direction in which the crank 22 is turned. The screw 17 at the end adjacent the crank 22 has a reduced portion 23 rotating in the bearing 24.

In order to push the filling material contained in the box 14 into a cushion cover, I provide an I beam 25 with teeth 26 struck into the top horizontal portion thereof. At one end of the beam 25, I provide a pushing

plate 27 secured to the beam 25 in any suitable manner, such as by angle irons 28. The beam 25 is supported in a position horizontal to support 12 in a guide 29 and a guide 30, thus assuring a horizontal movement to the beam 25 when pushed through the box 14 in a manner to be described. The guide 30 is an upstanding member integrally secured to the end of the support 12, and the 10 guide 29 is secured to the support 12 at a point adjacent the rear end of the box 14.

The beam 25 and the plate 27 will now be termed a pusher rod 31. In order to push the filling material out of the box 14, I provide a collar 32 encircling the beam 25 (Fig. 5). In a slot 33 in the top of the collar 32, I pivotally secure an actuating dog 34 pivoted on a rod 35 connected to the collar 32. It will be noted that the dog 34 contacts at 20 36 with the teeth 26 of the beam 24. In order to maintain the dog 34 in contact with the teeth 26, I provide a spring 37 mounted in a recess 38 in the collar 32 and exerting an upward force on the end 39 of the dog 34.

25 The pusher rod 31 is actuated by the dog 34 through the intermediary of a simple lever arrangement. This consists of a foot pedal 40 pivoted at 41 to the stay 13 and guided in a guide 42 secured to the standard 11. To 30 the foot pedal 40 and the standard 11, I pivotally secure a lever mechanism consisting of members 43 and 44. The member 44 is pivotally secured at one end to the standard 11, and at the other end to the member 43. 35 A link element 45 is connected to an intermediate point on the member 44 and to a depending ear 46 on the collar 32. It is thus apparent that a downward movement of the foot pedal 40 will act on the elements 43, 44 40 and 45 to move the collar 32 and in turn the pusher rod 31, through the intermediary of the dog 34 towards the box 14. I provide a strong coiled spring 47 connected to an ear 48 on the support 12 and to the foot pedal 45 40 at 49 in order to assure the return of the foot pedal 40 to its original position upon release of the actuating force. A downward movement of the foot pedal 40 will tend to move the pusher rod 31 only a short distance 50 through the box 14, and when the foot pedal 40 returns to its original position, the collar 32 and the dog 34 is forced backwards over the teeth 26, by means of the lever mechanism 43, 44 and 45. It is thus apparent, that in 55 order to push the pusher rod 31 through the box 14, the foot pedal 40 has to be depressed a sufficient number of times.

As the pusher rod 31 progressed through the box 14, the filling material therein is compressed and exerts a back pressure tending to force the pusher rod 31 backwards. In order to prevent this backward movement of the pusher rod 31, I provide a dog 50 contacting with the teeth 26 and pivoted at 51 in the 60 guide 30. The dog 50 is maintained in this

position by a coiled spring 52 which is secured to the dog 50 at one end, and to the guide 30, by means of a bolt 53, at the other end. To release the dog 50 from the teeth 26, I provide a connecting rod 54 screw-threaded at 55 to the dog 50, and a link 55 connected to the lower extremity of the rod 54. The link 55 is readily accessible to the operator and by pulling thereon, the dog 50 is forced upwards against the action of the spring 52 to the position indicated in dotted lines. (Fig. 4.)

The parts 15, 16 forming the box 14 are hinged at 56 to provide lids that can be readily opened in order to fill the box 14 with the filling material. The lids are maintained in a closed position by means of an L-shaped member 57 pivoted in a socket 58 in the block 19 and capable of rotation in a horizontal plane.

The machine is operated as follows: an operator sitting on a stool in front of the machine holds a cover or casing for the cushion over the forward end of the box 14. The foot pedal 40 is pushed down a sufficient number of times, until the pusher rod 31 has forced the filling material into the cover. The operator then pulls the link 55, and causes the dog 50 to assume the position shown in dotted lines in Fig. 4. This permits a backward movement of the pusher rod 31 due to the pressure existing in the box 14. In its backward movement, it carries the dog 34 with it, and the end 39 thereof contacts with the dog 50 and releases the dog 34 from the teeth against action of the spring 37. This permits the pusher rod 31 to be drawn back and ready for the next operation.

I claim:

1. In a machine for filling cushions, a stationary box, and a pusher rod having teeth thereon, means for pushing said pusher rod through said box, said means comprising a dog contacting with the teeth on the pusher rod, pivoted means contacting with said teeth for preventing backward movement of the pusher rod, and a means for releasing said last named means from said teeth, said pivoted means when released, operating with said dog to permit free backward movement of said pusher rod.

2. In the combination as set out in claim 1 in which the pivoted means comprises a dog and a spring for maintaining said dog in contact with the teeth on the pusher rod.

3. In a machine for filling cushions, a box, a pusher rod, means for urging the rod in a step-by-step manner into the box, means holding the rod against reverse movement, means for releasing said holding means, whereby the pressure in the box serves to move the pusher rod outwardly, and means whereby the reverse movement of the pusher rod acts to release the urging means.

4. In a machine for filling cushions, a box,

a pusher rod, means for urging the rod in a step-by-step manner into the box, means holding the rod against reverse movement, means for releasing said holding means, whereby
5 the pressure in the box serves to move the pusher rod outwardly, said holding means and said urging means contacting upon such reverse movement to release the urging means.

10 In testimony whereof I have hereunto set my hand.

CHARLES HENNELL.
